UNITED STATES PATENT OFFICE.

ANDREW P. ANDERSON, OF STOUGHTON, WISCONSIN.

HARROW.

SPECIFICATION forming part of Letters Patent No. 651,332, dated June 12, 1900.

Application filed March 1, 1900. Serial No. 6,976. (No model.)

To all whom it may concern:

Be it known that I, ANDREW P. ANDERSON, a citizen of the United States of America, residing at Stoughton, in the county of Dane 5 and State of Wisconsin, have invented certain new and useful Improvements in Harrows, of which the following is a specification, reference being had therein to the accompanying drawings.

10 This invention relates to certain new and useful improvements in harrows, and relates more particularly to that class generally known as "wheel-harrows" or "sulky-harrows."

15 The invention has for one object to construct a harrow of this type with a series of vibratory or longitudinally-oscillating drag-bars arranged in two sets, with one of said sets actuated through gearing connected to 20 the one drive-wheel and the other of said sets actuated through like gearing connected with the opposite drive-wheel.

Another object of the invention is to construct a harrow of this type in which each 25 drag-bar will be independent of the other drag-bars for elevation to pass an obstruction or the like, together with means whereby all the drag-bars of each set may be simultaneously elevated to the inoperative position or lowered to their working position, which operation may be controlled by the driver from his seat by the movement of a single lever.

A still further object of the invention is to provide means for operating both gears from 35 a single lever within easy reach of the driver's seat and to provide a frame of rigid construction which may, if desired, be constructed from ordinary angle-iron.

The invention further consists in the novel 40 construction, combination, and arrangement of parts, as will be hereinafter more specifically described and then particularly pointed out in the claims.

Briefly described, the elements entering into 45 the combination in my improved harrow are a frame of especial construction, the axles for the drive-wheels, journaled in said frame, the drive-wheels mounted on said axles, the two trains of gearing, and the series of drag-bars, 50 these latter divided into two sets, one set for each train of gearing. These drag-bars have

a vibrating or oscillatory movement when in the working position during the travel of the harrow and are pivotally supported at their forward ends in such a manner that when one 55 of the bars engages a stone or like obstruction the other bars will not be affected thereby; but the bar alone that engages the obstruction will elevate, so as to clear such obstruction. At their rear ends these drag-bars are 60 swiveled from a cross-rod in such a manner as to permit their vibratory movement and also the independent elevating or lowering of one bar with respect to the remainder. An elevating and lowering frame for the drag-bars 65 is carried by the truck-carriage frame and is operated by a lever located adjacent to the driver's seat, while by means of a separate lever, also located adjacent to the driver's seat, the clutches controlling the two trains 70 of gearing are thrown into or out of operative relation. All of this construction, together with the minor details, will now be described specifically, and in such description, reference will be had to the accompanying drawings, forming a part of this specification, and wherein like numerals of reference will be employed for designating like parts throughout the several views of the drawings, in 75 which—

80 Figure 1 is a top plan view of my improved harrow, showing the relative position of the two cranks which operate the vibratory or oscillating drag-bars. Fig. 2 is a longitudinal sectional view of the harrow, taken on the line 85 2 2 of Fig. 1. Fig. 3 is a rear view showing the drag-bars in the operative or working position. Fig. 4 is a detail sectional view of a part of one of the drag-bars, the vertical arm to which the drag-bars are pivotally connected at their rear ends, and of the horizontal arm which connects the drag-bars with the operating-cranks. Fig. 5 is a detail perspective view of a part of the truck-carriage frame, the pivoted elevating and lowering 90 frame for the drag-bar, and also showing one of the drag-bars and its connection with the operating-crank. Fig. 6 is a detail perspective view of one of the sleeves which form the swivel or toggle-joint connection for the 95 rear end of each drag-bar.

100 I will first refer to the construction of the

frame, which of the form herein shown is light, yet serviceable and durable. This frame consists of the side rails 1, which in the form herein shown are constructed of ordinary angle iron or steel and are connected at their front ends by a cross-brace 2, likewise of angle iron or steel with the ends bent inward and bolted, riveted, or otherwise rigidly secured to the side rails 1. Arranged outside of these side rails 1 is a pair of auxiliary side rails 3 of shorter length than the side rails 1 and composed of angle iron or steel, with their ends 3' bent inwardly and rigidly secured to the side rails 1. A flat cross-brace 4 extends underneath the side rails 1, near the forward ends thereof, and has its ends rigidly secured to the outer faces of the auxiliary side rails 3, near the forward ends thereof. A similar flat cross-brace 5 extends underneath the side rails 1, near the rear ends thereof, and has its ends rigidly secured to said side rails 1. Centrally supported on these two cross-braces 4 and 5 is a beam 6, a convenient form for which I have found to be the ordinary channel-bar, which beam, together with the side rails 1, forms supports for the bearings in which the operating-cranks of the drag-bars are journaled. Mounted upon the side rails 1 and the auxiliary side rails 3 are bearings 7, 7, in which are journaled the axles 8, 8, having the drive-wheels 9 mounted thereon. The hub of each of these drive-wheels is provided with a rigid clutch-section 10, adapted to be engaged by the movable clutch 11, slidably mounted on the axles 8.

Journalized in bearings 12, 12 on the side rails 1 and auxiliary side rails 3 and in a bearing 14, mounted upon the beam 6, are the operating-cranks 15 and 16 for the drag-bars, the one crank being driven from one drive-wheel and the other crank from the opposite drive-wheel. These cranks are driven by gears 17, mounted upon the axles 8, which mesh with gears or pinions 18, mounted upon the cranks 15 and 16, respectively. The rods or shafts composing the cranks have their crank portions alternating in position, so that when one drag-bar is at the forward limit of its movement the adjacent drag-bar on each side thereof will be at the limit of its rearward movement. By providing two of these operating-cranks with a separate gearing for each crank two sets of drag-bars are formed, one driven by one crank and the other set by the other crank. The drag-bars 19 are provided with a series of teeth 20, arranged therein in two rows, or, in other words, in zigzag position—that is, each alternate tooth being placed in the drag-bar adjacent to the opposite side from that of the preceding tooth. These drag-bars are preferably provided on their forward ends with a strap 21, which is doubled and secured to the upper and lower faces of the drag-bar, the loop thus formed and projecting beyond the forward end of

the bar acting as a buffer for the bar in event of its engaging a stone or like obstruction in the soil. The drag-bars are supported at their forward ends by a chain or link 70 connection 22 with a cross-bar 23, having its ends pivotally connected to a yoke 24, which forms a part of the frame for elevating and lowering the drag-bars and is pivotally supported at its ends from the side rails 1 of the 75 main frame. At their rear ends these drag-bars have an eye 25 secured therein, to which is pivotally attached an arm or rod 26, capable of both a vibrating movement, as required by the drag-bar in its operation, and of a vertical movement to permit the independent movement upwardly of each drag-bar when required. To support these drag-bars at the rear end thereof and also to simultaneously elevate and lower the same when desired, I 80 pivotally attach to the side rails 1, near their rear ends, a yoke 27, in the angularly-extending ends 28 of which is mounted a cross-shaft 29. Upon this shaft 29 is mounted a series of double sleeves, consisting of two members 90 30 and 31, the former extending horizontally and receiving therein the shaft 29 and the latter extending transversely to the former or in a vertical position to receive the rods or arms 26, which are pivotally connected at 95 their lower ends to the rear ends of the drag-bars. These rods or arms 26 are bifurcated at their upper ends to receive stems 32, secured therein, preferably by both a metal rivet or screw 33 and a wooden pin 34. This 100 construction is provided so that in the event of a sudden blow being delivered against any one of the drag-bars the plug or pin 34, being the weaker part, will naturally break first, and the rigidity of the joint between the rod 26 and 105 stem 32 being thus broken no further damage will be done to the parts. These stems in their part projecting above the rods or arms 26 are likewise bifurcated to receive the end of a metallic bar 35, which is pivotally attached by a 110 rivet to said stem and has its under edge cut away, as at 36, so as to permit the full sweep as required by the drag-bar in its movement. This bar is securely fastened in the rear ends of the crank-arms 37, one of which is provided 115 for each drag-bar and which connect at their other ends with the cranks 15 and 16, respectively. When these crank-arms are constructed of wood, I may attach them to the cranks by cutting out a part of the forward ends, as 120 shown at 38, placing the cranks in this end of the arm, and then securing the part 38 in its position by bolts 39. Likewise when these arms are constructed of wood in order to prevent the splitting of the same I preferably 125 slit the rear ends of the same, insert the bars 35 therein, and secure the same by rivets 40, placing within the crank-arms at the termination of the slit for the reception of the bar 35 a pin or rivet 41, against which the inner 130 end of the said bar may seat itself.

For the purpose of simultaneously elevat-

ing and lowering the drag-bars, I attach to the yokes 24 and 27, centrally thereof, a yoke-lever 42 and pivotally connect to the side of the beam 6 a lever 43, which is connected by 5 a link or strap 44 to the yoke-lever 42, so that when the said lever is moved backward it simultaneously operates and moves downwardly the yokes 24 27, elevating the angular ends thereof, and consequently elevating 10 at the same time the cross-bar 23 and rod or shaft 29 and carrying the drag-bars upward therewith.

In order to engage both trains of gearing at the same time, and thus cause the simultaneous operation of both sets of drag-bars, 15 I provide two angularly-shaped levers 45 and 46, each having forked ends to engage the respective clutches 11 on the drive-axles. These two clutch-operating levers are each provided 20 with oblong slots 47 to receive headed pins 48 at the front ends of the side bars 1, the lever 45 having its end pivotally attached to one end of a link 49 and the lever 46 having its end similarly attached near the opposite end 25 of said link, the link being in turn pivotally supported upon a saddle 50, attached to the cross-brace 2 and beam 6, so that when said link is actuated the ends of the levers 45 46, attached thereto, will be simultaneously 30 moved toward or away from each other, according to the direction in which the link is moved, and the clutches 11 consequently be simultaneously engaged with or disengaged from the clutch-sections carried by the hubs 35 of the drive-wheels. The inner end of this pivoted link 49 is bent upwardly and provided with a notch 51 to receive the end of the operating-lever 53, pivotally supported on the saddle 50, said lever being held so as to retain 40 the clutches in engagement or in the inoperative position by the rack-bar 54, mounted upon the saddle 50. A seat 52 may be suitably supported either from the cross-brace 4 or from the beam 6, and a foot-rest 55 may 45 be attached to the saddle 50 or at any point desired. The saddle 50 may, if desired, be extended, as shown, beyond the front cross-bar for attaching the draft-equalizer thereto, and the tongue 56 may be connected to the 50 front cross-bar in any desirable or suitable manner.

I will now briefly describe the operation, assuming the parts to be assembled as shown in Fig. 1 of the drawings, and the lever 53 55 being in the position shown in this view, so as to cause the engagement of the clutches. Upon the forward movement of the harrow the gears or pinions 17 18 cause the independent rotation of the crank-rods 15 16, operating the crank-arms 37 and imparting a vibratory movement to the rods or arms 26 to cause the oscillation of the drag-bars 19. The cranks of these crank-rods being set alternately or at the half, it will be observed 60 that each alternate drag-bar of each set is at the forward limit of its stroke when the re-

maining drag-bars of each set are at the limit of their rear stroke, and upon the engagement of any one of the bars with an obstruction the links forming the connection 22 between the forward end of the bar and the bar 23 will by their collapsing or doubling upon each other permit the elevating of this bar independently of all the other bars, so that the operation of the remaining drag-bars will 70 not be interfered with, and by reason of the rods or arms 26 sliding vertically within their sleeves 31 the elevation of the bars at their rear ends will be permitted, as well as at the front end, so that such obstructed bar may 75 pass readily over its obstruction.

When moving the harrow from one field to another or at other times when it is not desired for the drag-bars to operate, the lever 53 is thrown so as to disengage the clutches, 80 the lever 43 thrown backward, and the drag-bars elevated to a position underneath the main frame of the harrow.

While I have herein shown and also described the various elements in detail and also 90 the manner of assembling the same, it will of course be evident that in the construction of the harrow various changes may be made in the details thereof without departing from the general spirit of my invention. 95

Having fully described my invention, what I claim as new, and desire to secure by Letters Patent, is—

1. In a wheel-harrow, the combination, with the supporting-frame, of two independent 100 sets of oscillatory drag-bars adapted to operate longitudinally of the frame, separate operating means for each set of drag-bars, and means for simultaneously elevating and lowering all of the drag-bars. 105

2. In a wheel-harrow, the combination, with a supporting-frame, of two independent sets of oscillatory drag-bars pivotally supported from the frame and adapted to operate longitudinally thereof, means for operating said 110 drag-bars, and means for simultaneously elevating and lowering all of the drag-bars, substantially as described.

3. In a harrow, the combination, with the supporting-frame, of a series of independent 115 pivotally-supported oscillatory drag-bars, means for operating said bars in the same direction as the harrow is moving, and means for simultaneously elevating and lowering said bars, substantially as described. 120

4. In a wheel-harrow, the combination, with the supporting-frame, the independent drive-axles journaled therein, and the drive-wheels mounted on said axles, of a series of independent oscillatory drag-bars pivotally supported from said frame, means for operating said bars longitudinally of the frame, and means for simultaneously elevating and lowering said bars, substantially as described. 125

5. In a wheel-harrow, the combination, with the truck and frame, of a series of oscillatory drag-bars pivotally supported from the frame 130

- and adapted to oscillate longitudinally of the frame, and means for operating said drag-bars, substantially as described.
6. In a wheel-harrow, the combination, with the truck and frame, of a series of oscillatory drag-bars pivotally supported from the frame and adapted to oscillate longitudinally of said frame, means for operating said drag-bars, and means carried by the frame for simultaneously elevating and lowering all of the bars, substantially as described.
7. In a wheel-harrow, the combination, with the truck and frame, of a series of independent drag-bars pivotally supported from the frame, means for operating said bars in an oscillatory manner longitudinally of the frame, and means for elevating and lowering said bars, substantially as described.
8. In a wheel-harrow, the combination, with the frame, of two independent sets of drag-bars pivotally supported from said frame, a pair of cranks journaled in the frame, one for each set of drag-bars, means for operating said cranks, and crank-arms connecting said cranks to the drag-bars for operating the latter when the cranks are operated, substantially as described.
9. In a harrow of the class described, the combination, with the frame and a series of drag-bars pivotally supported from said frame, of means for operating said drag-bars to impart an oscillatory movement thereto longitudinally of the frame, means carried by the frame for simultaneously elevating and lowering all of the bars, and means carried by the frame for simultaneously throwing each of said bars into or out of gear, substantially as described.
10. In a harrow of the class described, the combination, with the frame, of a series of independent drag-bars pivotally supported at each of their ends from said frame, each of said drag-bars having a buffer on its forward end, and means for imparting an oscillatory movement to said bars longitudinally of the frame.
11. In a harrow of the type described, the combination, with the frame, of a series of independent drag-bars having zigzag teeth, each bar being pivotally supported at its ends from the frame and provided at the forward ends with buffers, and means for operating said bars longitudinally of the frame, substantially as described.
12. In a harrow of the type described, the combination, with the frame, of a series of drag-bars pivotally supported at each of their ends from said frame, means for operating said bars longitudinally of the frame, a pair of pivoted yokes carried by the frame, an operating-lever, and connections between said lever and yokes for elevating and lowering said bars, substantially as described.
13. In a harrow of the type described, the combination, with the frame, of the independent drive-axles journaled therein, drive-wheels mounted on said axles, a series of pivotally-supported drag-bars adapted to operate longitudinally of the frame alternating in their forward and backward stroke, and means for operating said bars, substantially as described.
14. In a harrow of the type described, the combination, with the frame, of a series of pivotally-supported drag-bars adapted to operate longitudinally of the frame, and means for operating said bars alternately in their forward and backward stroke.
15. In a harrow of the type described, the combination, with the frame, of a series of independent drag-bars pivotally supported from said frame and adapted to operate longitudinally thereof, means for operating said bars alternately, whereby when each alternate bar is at the forward limit of its stroke the remainder of said bars will be at the backward limit of their stroke, and means for simultaneously elevating and lowering all of the bars, substantially as described.
16. In a harrow of the type described, the combination, with the frame, of a series of drag-bars pivotally supported therefrom and capable of independent elevation at either end, and means for operating said bars longitudinally of the frame, substantially as described.
17. In a harrow, the combination, with the frame, of a series of pivotally-supported drag-bars, a pair of cranks journaled in the frame, gearing carried by the frame for operating said cranks, and means connected to said cranks and to the rear ends of the drag-bars for operating the same longitudinally of the frame, said bars operating alternately of the series, substantially as described.
18. In a wheel-harrow, the combination, of the frame, the drive-axles journaled therein, the drive-wheels mounted on said axles, a pair of cranks journaled in the frame, gearing carried by said frame for said cranks, means arranged on the frame for operating the gearing for each of said cranks simultaneously, a series of drag-bars pivotally supported from the frame at each of their ends, connections between said cranks and the rear ends of said bars for imparting a longitudinal movement thereto, and means carried by the frame for elevating and lowering said bars, substantially as described.
19. In a harrow of the type described, the combination, with the frame, of a pair of cranks journaled in said frame, independent operating-gears for each of said cranks, means carried by the frame for simultaneously operating said gears, a series of drag-bars pivotally supported from the frame and adapted to operate longitudinally thereof, crank-arms connected to the rear ends of said bars for operating the same as the cranks are operated, a pair of pivoted yokes carried by the frame, a lever connecting said yokes, an operating-lever pivotally connected to said

frame and to said lever for simultaneously operating said yokes and elevating both ends of said bars, substantially as described.

20. In a wheel-harrow, the combination, with the supporting-frame, of a series of drag-bars independently supported from said frame at each end and each capable of elevation at either end independently of the other bars, and means for operating said bars, substantially as described.

21. In a wheel-harrow, the combination, with a supporting-frame, of a series of drag-bars each pivotally supported at each end from said frame and adapted to operate longitudinally thereof, each of said bars provided with zigzag teeth and having a buffer on its forward end, and means for operating said bars, substantially as described.

22. In a wheel-harrow, the combination, with the frame, of a series of pivotally-supported drag-bars, a pair of cranks journaled in said frame, separate gearing for each of said cranks, a pair of angular levers supported on the frame and connected to said gearing, and a hand-lever pivotally supported from the frame for simultaneously operating said angular levers, a crank-arm connected to each of said drag-bars and to said cranks, a pair of pivoted yokes carried by the frame, a lever connecting said yokes, and an operating-lever pivotally connected to said frame and to said lever for operating said yokes to simultaneously elevate and lower both ends of the drag-bars, substantially as described.

23. In a harrow of the type described, the combination, of two sets of longitudinally-movable drag-bars pivotally supported from a frame, the independently-operated cranks for each set of drag-bars, and means for simultaneously elevating and lowering both sets of drag-bars, substantially as described.

24. A sulky-harrow comprising in combination, with the frame and drive-wheels, a series of drag-bars pivotally supported at each end from said frame and each capable of elevation independent of the other bars, of means for operating said bars longitudinally of the frame and alternating said bars in their forward and backward stroke, substantially as described.

25. A wheel-harrow comprising in combination with the frame and drive-wheels, a series of drag-bars pivotally supported from the frame at their forward ends, and means connected to the rear ends of said bars for operating the same longitudinally of the frame, substantially as described.

26. A wheel-harrow comprising in combination with the frame and drive-wheels, a series of drag-bars pivotally supported from the frame at their forward ends, a buffer carried by the forward end of each of said bars, and means connected to the rear ends of said bars for operating the same longitudinally of the frame.

27. In a wheel-harrow, the combination,

with the frame and drive-wheels, of a series of drag-bars pivotally supported from the frame at their forward ends, means connected to the rear ends of said bars for operating the same longitudinally of the frame, and means carried by the frame for simultaneously elevating and lowering said bars.

28. In a wheel-harrow, the combination, with the frame and drive-wheels, of a series of drag-bars pivotally supported from the frame at their forward ends and each capable of elevation independently of the other bars, means connected to the rear ends of said bars for operating the same longitudinally of the frame and alternating said bars in their forward and backward stroke, and means carried by the frame for simultaneously elevating and lowering said bars.

29. In a wheel-harrow, the combination, with the frame and the drive-wheels, of a series of independent drag-bars pivotally supported at each of their ends from said frame, a buffer carried on the forward end of each of said bars, and means connected to each of said bars at their rear ends for imparting an oscillatory movement to the bars, substantially as described.

30. In a wheel-harrow, the combination, with the frame and the drive-wheels, of a series of independently-supported drag-bars pivotally suspended at each of their ends from said frame, and means connected to each of said bars at their rear ends for imparting an oscillatory movement to the bars, substantially as described.

31. In a wheel-harrow, the combination, with the frame and drive-wheels, of a series of independently-supported drag-bars pivotally suspended at each of their ends from the frame, and means connected to each of said bars for imparting an oscillatory movement to the bars longitudinally of the frame.

32. In a wheel-harrow, the combination, with the frame and drive-wheels, of a series of independently-supported drag-bars pivotally suspended at each end from said frame, means connected to each of said bars for operating the same longitudinally of the frame, and means for simultaneously elevating and lowering said bars, substantially as set forth.

33. In a wheel-harrow, the combination, with the frame and drive-wheels, of a series of independently-supported drag-bars pivotally suspended at each end from the frame, means connected to each of said bars at their rear ends for imparting an oscillatory movement to said bars longitudinally of the frame, and means carried by the frame for elevating and lowering said bars.

34. In a wheel-harrow, the combination, with the frame and drive-wheels, of a series of independently-supported drag-bars pivotally suspended at each end from the frame, means connected to each of said bars for imparting an oscillatory movement to the same longitudinally of the frame and alternating

the forward and backward stroke of the bars, and means carried by the frame for elevating and lowering the bars.

35. In a wheel-harrow, the combination with the frame and drive-wheels, of a series of independently-supported drag-bars pivotally supported at each end from the frame, means connected to each of said bars at their rear ends for imparting an oscillatory move-

ment to said bars and alternating the forward and backward stroke of the bars.

In testimony whereof I affix my signature in the presence of two witnesses.

ANDREW X P. ANDERSON.
